UNITED STATES PATENT OFFICE

149,424

DESIGN FOR A DESK CALENDAR

Edward Kottle, Lynbrook, N. Y.

Application November 29, 1947, Serial No. 142,883

Term of patent 7 years

(Cl. D74—5)

To all whom it may concern:

Be it known that I, Edward Kottle, a citizen of the United States, residing in Lynbrook, Nassau County, New York, have invented a new, original, and ornamental Design for a Desk Calendar, of which the following is a specification, reference being had to the accompanying drawing, forming part thereof.

Fig. 1 is a top plan view of desk calendar, showing my new design, the printed matter shown in Figs. 1 and 2 being merely representative of that which would appear on the calendar from time to time.

Fig. 2 is a view in elevation from the front.

Fig. 3 is a view in elevation from the rear.

I claim:

The ornamental design for a desk calendar substantially as shown and described.

EDWARD KOTTLE.
